UNITED STATES PATENT OFFICE.

MORRIS PHILIP, OF NEW YORK, N. Y.

BLOOMER-SKIRT.

1,250,004.

Specification of Letters Patent. Patented Dec. 11, 1917.

Application filed April 19, 1917. Serial No. 163,105.

To all whom it may concern:

Be it known that I, MORRIS PHILIP, a subject of the Emperor of Austria, and a resident of the city of New York, borough 5 of Manhattan, in the county and State of New York, have invented a new and Improved Bloomer-Skirt, of which the following is a full, clear, and exact description.

This invention relates to wearing apparel 10 and particularly to a child's garment and has for an object the provision of an improved construction whereby the garment may be arranged for use as a skirt or arranged for use as bloomers.

Another object in view is to provide a 15 combined skirt and bloomer garment so that the same fastening means may be used for holding the garment in proper position as a skirt or in proper position as a bloomer.

A still further object of the invention is 20 to provide a skirt which is formed with means for dividing the skirt into sections, and the provision of means for puckering each section or leg to produce a bloomer 25 effect.

In the accompanying drawing:

Figure 1 is a perspective view of a skirt embodying the invention.

Fig. 2 is a perspective view of the skirt 30 shown in Fig. 1 arranged on a figure.

Fig. 3 is a perspective view of a garment shown on a figure and arranged as a pair of trousers.

Fig. 4 is a view similar to Fig. 3 but 35 showing the lower end of the legs puckered or converted into a bloomer structure.

Fig. 5 is a perspective view of the garment shown in Fig. 3 looking at the same from the bottom.

Fig. 6 is an enlarged detail fragmentary 40 sectional view through Fig. 2 on line 6-6.

Referring to the accompanying drawing by numerals, 1 indicates the skirt as an 45 entirety, the same being provided, if desired, with a waist band 2 and with plaits 3 and 4 at the rear. Also, plaits 5 and 6 are provided at the front, said plaits being preferably of the variety known as box plaits so as to provide a fullness which will hide the 50 buttons and other connecting means when the device is in use as a skirt and which will not produce a bad appearing structure when the device is used as bloomers.

The skirt 1 is provided with an opening 7 55 at the front and an opening 8 at the back,

said openings extending for any desired distance, preferably slightly less than half the length of the skirt. By reason of these two openings sections or legs 9 and 10 will be formed which, when arranged as shown in Fig. 4, will produce a bloomer effect and when connected as shown in Fig. 1 will produce a skirt. At the point of connection at both the front and rear there is provided a strip 11 formed with a number of buttonholes 12 for receiving the respective buttons 13 secured to the strip 14. The strip 11 is connected to the leg section 9 while strip 14 is connected to the section 10, as shown more particularly in Fig. 6.

It will be observed that the buttonhole strip 11 is completely out of sight and the strip 14 is almost completely hidden, though the same overlaps section 11. This construction is necessary not only in connecting the skirt together as shown in Fig. 1 but when connecting the same as shown in Figs. 3, 4 and 5, in which instance the strip 14 of leg 10 would be connected to the strip 11 of the same leg and thereby produce a round leg structure as shown in Fig. 5. The strip 14 of the leg section 9 will also be connected to the strip 11 of the same leg section. Buttons and buttonholes have been provided as shown in the drawing, but it will be evident that hooks and eyes or other connecting means may be used without departing from the spirit of the invention.

In order to pucker the lower ends of the legs and to produce a proper bloomer effect, 90 draw strings 15 and 16 are provided, draw string 15 being connected at 17 and 18 to section 9 while draw string 16 is connected at 19 and 20 to section 10, said draw strings fitting in the usual hem 21 provided in the 95 skirt. Upon drawing the center or the exposed part of the draw strings 15 and 16 the sections 9 and 10 will be puckered at the lower end and said pucker may be maintained by forming a knot in each of the 100 draw strings and adjusting the parts as shown in Fig. 4. By unbuttoning the parts from the position shown in Fig. 4 and again buttoning them as shown in Fig. 1 the garment will be changed back into a skirt 105 formation as shown in Fig. 1. A minimum number of fastening means have been provided for holding the parts of the skirt together when arranged as a skirt and the same fastening means when holding the 110

parts together when the garment is arranged as bloomers.

What I claim is:

5 A bloomer skirt comprising a skirt body provided at the front and back with openings, means for normally connecting the walls of said openings together edge to edge,

and means for connecting the edge of the garment at the openings so as to produce a pair of leg structures, said body being formed with a box plait on each side of said openings to cover said openings when the parts are connected together edge to edge.

MORRIS PHILIP.
